UNITED STATES PATENT OFFICE.

IVAN ENGSTROM, OF CHICAGO, ILLINOIS.

CARRY-OVER MECHANISM.

Original application filed June 12, 1922, Serial No. 567,741. Divided and this application filed December 14, 1922. Serial No. 606,362.

To all whom it may concern:

Be it known that I, IVAN ENGSTROM, a citizen of the United States, residing at Chicago, in the county of Cook and State of Illinois, have invented a new and useful Improvement in Carry-Over Mechanisms, of which the following is a specification.

My invention relates to carry-over mechanisms for use with adding machines, and is characterized by a construction which stores the carry-over during operation of the adding mechanism and then advances by release of the carry-over mechanism, the stored carry-over values. My mechanism is constructed so that separate mechanism for each order higher than the lowest is first set in operative position to advance the adding indicator of next higher order than an indicator that passes from its "9" to its "0" indication, after which said separate mechanisms operate one after the other to advance the adding indicators into which the carrying is to be effected, each one step. In this manner the carry-over operation can not be lost since it is effective only after the operation of the adding indicators has been completed for any complete adding operation, and, furthermore it is impossible for inaccuracy to result from the carrying operation since each carrying mechanism operates only after the operation of the next carrying mechanism in the series has been completed.

This is a divisional application of my pending application, Serial No. 567,741, filed June 12, 1922, which latter application is a renewal of my application Serial No. 135,025 filed December 4, 1916.

My invention will best be understood by reference to the accompanying drawings showing a preferred embodiment thereof in which

Fig. 1 shows in plan view an adding mechanism provided with my improved carry-over mechanism,

Fig. 2 is a view taken along the line 2—2 in Fig. 1 and shows the operating and control mechanism for the adding and carry-over mechanism,

Fig. 3 is an enlarged view of the adding mechanism in the operated position of the carry-over mechanism,

Figs. 4 and 5 are detail views of the holding devices employed in connection with the carry-over mechanism shown in Fig. 3,

Fig. 6 is a plan view of part of the adding mechanism removed from the remaining portions thereof,

Fig. 7 is an enlarged vertical sectional view of one of the total indicating wheels removed from its supporting shaft, taken along the line 7—7 in Fig. 8,

Fig. 8 is a sectional view of the parts shown in Fig. 7 taken along the line 8—8, and

Fig. 9 is a left hand elevation of the parts shown in Fig. 7.

Similar numerals refer to similar parts throughout the several views.

The operating mechanism of the machine consists, as shown in Fig. 2, primarily of a plurality of ordered operating slides 100 slotted longitudinally and supported longitudinally of the machine by transverse rods 101 and 102 extending between and supported by the side plates of the machine. Each of the operating slides has near its rear end a downwardly extending lug 103 carrying a roller 104 for engagement with an operating lever 105 carried by a rock shaft 106. The rock shaft 106 has rigidly secured thereto a crank 110 carrying at its outer left hand end as shown in Fig. 2 a roller 111 which rests against the surface of a cam 112 rigidly secured to the operating shaft 113. An operating handle not shown is carried by the shaft 113. As a result of the construction described, when the handle is moved forwardly the crank 110 is rotated and with it the rock shaft 106. The rock shaft 106 also carries a third lever 116 rigidly secured to the rock shaft for engaging the front side of the roller 104 carried by the corresponding operating slide 100. Each of the levers 105 is free to turn upon the shaft 106 except as it is prevented therefrom by a helical spring 117 located upon the shaft 106 and engaging at one end the rear edge of the lever 105 and at the other end a pin 118 extending from the lever 116. The spring 117 is made sufficiently strong to drive all of the mechanism actuated by the operating slide 100 and forms a yielding connection between the operating lever 105 and the shaft 106 permitting continued operation of the shaft 106 if the slide 100 is stopped in its motion before it has been moved an amount corresponding to the full amount of operation of the rock shaft.

Each operating slide 100 is in line with stops controlled by a series of keys, not

shown, of the same order, as a result of which the amount of motion of any operating slide for a cycle of operation of the operating shaft is determined by the particular 5 stop of the corresponding order lying in its path as a result of a particular set-up on the keyboard. After engaging the various stops of the keyboard mechanism, the operating slides 100 remain in their stopped positions 10 for continued forward motion of the operating handle and when the operating handle is moved in a backward direction to continue its cycle of operation and the cam 112 is rotated to permit the rock shaft 106 to return 15 to its normal position a returning spring 119 moves said crank 110 and the rock shaft 106 to return the same to normal position, thus rotating the levers 116 which by their engagement with the rollers 104 move the operating slides and the parts carried thereby 20 to their normal position.

Each of the operating slides 100 has formed on its upper edge a rack 100^a which, as indicated in Figs. 7 and 8, meshes with an 25 intermediate gear 122 loosely mounted on a supporting shaft 123. Each intermediate gear in turn meshes with a gear 124 carried by the shaft 125 which supports the total indicating wheels. Each of the gears 124 carries a pin 129 which, as more clearly shown 30 in Fig. 8, carries an operating pawl 130 for engaging the teeth of a ratchet wheel 131 carried by a total indicating wheel 132. Each of the gears 124 carries a spring 133 35 tending to hold its pawl 130 in engagement with the ratchet wheel 131. As a result of the construction described, when one of the operating slides 100 is moved toward the front of the machine the pawl 130 of the 40 corresponding order is moved backward on its ratchet wheel 131 a corresponding amount and when the said operating slide is returned to its normal position the ratchet wheel 131 and the total indicating wheel 132 connected 45 therewith are advanced an amount corresponding to the motion of the operating slide and, therefore, corresponding to the set-up of the corresponding series of keys of the keyboard.

50 An ordered carry-over mechanism is provided in connection with the total indicating mechanism constructed as follows: A plurality of spaced plates 145 is supported in vertical position longitudinally of the machine on the transverse rods 146, 147 and 148, which rods are rigidly supported by the side plates 126 and 127 of the adding mechanism. Each of the plates 145 is provided with a 55 downwardly extending arm 145^a to the lower end of which is pivoted at 149 a lever 150. The pivot 149 also supports a second lever 151 which is normally held by a spring 152 against a lug 153 carried by the lever 150. The lever 151 has pivoted to its lower end at 60 154 a latch 155 normally held in engagement

with a lug 156 on the lever 151 by a spring 157. The latch 155 has a downwardly extending arm in the path of a pin 158 carried by the corresponding lever 116, as a result of which, when the lever 116 is moved forwardly by the operation of the rock shaft 106, the lever 151 is rotated upon its pivot 149, which, through the operation of the spring 152 also rotates the lever 150 upon said pivot. The spring 152 permits the lever 116 to move the 70 lever 150 the full amount of possible motion of the latter, after which continued motion of the lever 116 moves the lever 151 relatively to the lever 150 to permit the pin 158 to pass the lower end of the latch 155. When 75 the lever 116 is returned to its normal position the spring 157 yields to permit the latch 155 to turn upon its pivot 154 thus permitting the pin 158 to pass the latch 155 without motion of the levers 151 and 150 to their 80 normal position.

As more clearly shown in Fig. 3, each of the levers 150 carries at its upper end a pin 159 working in a slot 160 in the lower end of the short arm of a bell crank carry 90 over pawl 161, which is pivotally supported at 162 on a sliding plate 163 mounted upon rods 164 and 165 extending between and carried by the side plates 126 and 127 of the adding mechanism. Slots 166 and 167 are 95 formed through the plate 163 to permit said plate to move transversely of said rods 164 and 165 in a horizontal direction. The carry over pawl 161 is provided with an upwardly extending arm 161^a the end 100 of which is in the plane of one of the ratchet wheels 131. The pawl has two positions, first, its operative or upper position in which the end of the arm 161^a engages the ratchet wheel 131 when the plate 163 105 moves toward the front of the machine, and an inoperative or lower position for which the end of the arm 161^a clears said ratchet wheel when the plate 163 is reciprocated on its supporting rods 164 and 165. The 110 long arm of the carry-over pawl 161 is extended beyond the arm 161^a to engage a holding latch 168 which, when in engagement with the carry-over pawl, holds it in 115 its lower or inoperative position. A torsion spring 169 is supported on a stud 170 extending from the plate 163 and the ends of this spring engage respectively a post or lug 171 projecting from the plate 163 120 and a lug 172 projecting from the carrying pawl 161. Near its left hand end, as shown in Fig. 3, the carrying pawl is provided with a slot 173 for receiving a headed stud 174 carried by the plate 163 to guide and hold the left hand end of the carrying pawl 125 171 in proper position relatively to its supporting plate 163. The holding latch 168 is rigidly secured to a tripping lever 175 which, together with the holding latch 168, 130 is pivotally supported upon a stud 176 pro-

jecting from and carried by the plate 163. The tripping lever 175 is in the plane of an operating lug 177 carried by the total indicating wheel 132 of next lower order 5 as a result of which, when the wheel 132 of said lower order passes from its nine to its zero indication, the operating lug 177 engages the tripping lever 175 to move the holding latch 168 from engagement with the left hand end of the carrying pawl 161 thus permitting the spring 169 to raise the carrying pawl to its operating position, for which position subsequent motion of the plate 163 and the carrying pawl towards the 10 front end of the machine advances the ratchet wheel 131 and the total indicating wheel 132 of next higher order one unit. A spring 178 carried by the stud 176 is provided which tends to hold the tripping 15 lever 175 and the holding latch 168 in the position indicated in Fig. 3, the ends of said spring resting respectively against a pin 179 and the connecting member between the tripping lever 175 and the holding latch 20 168. When the tripping lever 175 is actuated by the projecting lug 177, the lower end of the latch 168 is moved into a clearance slot 180 formed through the left hand end of the carrying pawl 161, the edge of which 25 slot holds said latch and tripping member in the position into which they are moved by the lug 177 as long as the carrying pawl 161 is in its raised position.

A holding pawl 181 pivotally supported 30 upon the rod 165 is provided for each of the ratchet wheels 131 for preventing back rotation of said ratchet wheel and the engaging end of the holding pawl is rounded as indicated at 181^a to slightly move the 35 ratchet wheel 131 to its proper angular position, assuming that the operation in a forward direction of the ratchet wheel 131 either by the corresponding operating slide or by the carrying pawl is not quite 40 sufficient for the corresponding tooth to quite clear the end of the holding pawl. The holding pawl 181 therefore not only serves to prevent back rotation of the ratchet wheel but also serves to bring said ratchet 45 wheel and the total indicating wheel 132 secured thereto into alignment with the reading line of the total indication of the total indicating wheels. Each holding pawl 181 is provided with a laterally extending arm 50 181^b which has an ear 181^c connected with its other end and lying in a plane parallel with the holding pawl and provided with an opening for receiving the rod 165, the ear 181^c and the holding pawl 181 being so spaced as indicated in Fig. 1 by the arm 181^b as to serve as a spacer for holding the plate 163 against the plate 145. This construction is more clearly shown in Fig. 6. A spring 182 is provided for each holding pawl 181, which spring is mounted upon 55 the rod 165 between the ear 181^c and the pawl 181 with its ends extending into engagement with the arm 181^b and a pin 183 carried by and extending away from the observer from the next plate 145, or towards the observer 60 from the particular devices shown in Fig. 3.

Each of the plates 145 has formed on its left hand edge a forwardly projecting arm 184 which carries at its forward end a horizontally projecting ear 185 for pivotally supporting at 186 a detent 187 for engaging a vertical flange 163^a extending laterally from the forward edge of the sliding plate 163 when said sliding plate is moved to its operated position, the end of the detent 187 being provided, as indicated in Fig. 4, with a shouldered portion 187^a for securing a desired amount of engagement between said detent and said flange. Each detent 187 carries a downwardly extending lug 187^b for receiving one end of a helical spring 188 the other end of which is supported upon the pin 171, as a result of which the spring 188 tends to move the detent 187 into its holding position for retaining the corresponding sliding plate 163 in its operated position when said sliding plate has been moved by the lever 150 to said operated position. The spring 188 also tends to return 70 said sliding plate 163 from its operated position to its normal position when such motion is permitted by the withdrawal of the corresponding detent 187. Each of the detents 187 is provided with a tripping arm 187^c engaged by the forward edge of the sliding plate 163 above its flange 163^a of next lower order than the sliding plate 163 engaged by the detent 187, as a result of 75 which, when a sliding plate 163 of lower order is released and returned to its normal position by the operation of its spring 188, it engages the tripping arm 187^c of the detent 187 of next higher order and moves said detent against the action of its spring 188 into releasing position, thus permitting 80 the corresponding sliding plate to return to its normal position, which in turn releases the detent of next higher order, and so on throughout the entire series of sliding plates, as a result of which the carrying pawls 161 85 move from their operated position towards the front end of the machine one after another beginning with the carrying pawl of lowest order and each carrying pawl completes its carrying operation before the carrying pawl of next higher order begins its forward movement. The tripping arm 187^d carried by the detent 187 of lowest order has its free end bent downwardly as indicated more clearly in Fig. 5 for effective engagement with a downwardly extending arm 189 carried by a rocking member 190 rigidly secured to a rock shaft 88.

The shaft 113 has rigidly secured thereto a second cam 225 which engages a roller 232 90

when the handle begins its motion towards the front of the machine, and is provided with a delay surface holding the roller 232 in operated position during the major part 5 of the motion of the handle and until just before said handle reaches its position of rest on its backward stroke. The roller 232 is carried by a lever 234 pivotally supported by the frame of the machine at 235. The 10 lever 234 has a projecting arm 234^a carrying a pin 236 engaging the forked end of an arm 237 carried by the shaft 88. A spring 238 is connected with the lever 234, tending to hold said lever in the position indicated 15 in Fig. 2. As a result of this construction the shaft 88 is rocked in a counterclock-wise direction by the beginning of the movement of the shaft 113 to move the slides 100 towards the front of the machine, which rocking 20 of the shaft 88 places the arm 189 in the position shown in Fig. 3, in which position it remains while the shaft 113 is completing its cycle of operation, or in other words until just before it reaches its position 25 of rest indicated in Fig. 2, by which time the total indicating wheels have been operated by the return movement of the slides 100 and the carry over pawls have been released to carry into the indicating wheels 30 any units required by the amount just added to the previous indication of the wheels. The roller 232 is then released from the cam 225, the spring 238 rocks the shaft 88 in a clock-wise direction as seen in Figs. 2 and 3, 35 the arm 189 engages the tripping arm 187^a and the detent 187 of lowest order is released and the carrying operation is effected in the manner described.

As a result of the construction described, 40 it will be seen that the sliding plates 163 of the carry-over mechanism are moved to their operated position by forward motion of the operating handle, in which position said sliding plates are held by the detents 187; during the return movement of the 45 operating handle the total indicating wheels 132 are operated and each is advanced an amount corresponding to the set-up of the keyboard for the corresponding order of units; each of the total indicating wheels which passes during its advance to its zero 50 position actuates the tripping lever 175 connected with the holding latch of next higher order thus permitting the carrying pawl of 55 said higher order to move to its upper or operative position, after which continued movement of the operating handle in its backward direction at the end of its operating cycle results in a rocking of the shaft 60 88, so that the rocking member 190 releases the detent 187 of lowest order which permits the sliding plate 163 of lowest order to move to its forward position and this by the release 65 of the second detent permits the movement of the second sliding plate 163 to its for-

ward position, and so on throughout the series of sliding plates, thus moving the carrying pawls one after another to their forward position and only advancing the totalizer wheels corresponding to the carrying pawls previously released from their holding latches, each one unit. As a result of this sequence of operation, there is no possibility of simultaneous operation of the total indicating wheels by the operating slides and the carrying pawls and there is, further, no possibility of simultaneous operation of the carrying pawls to operate the total indicating wheels which insures that the correct amount of advance shall be 70 imparted to each total indicating wheel by a complete cycle of operation to add to the previous total indication the amount set up on the keyboard mechanism. 75

After the operation of the adding mechanism as described, the forward motion of the operating handle during the next cycle of operation again returns the sliding plates 163 to their rear position and at the same time, through the operation of the levers 150 upon the carrying pawls 161, any of the carrying pawls released during the preceding cycle of operation are moved downwardly and held by their holding latches 90 in their lower position until again released by the operation of the total indicating wheels in the manner above described. 95

Provision is made for setting all of the total indicating wheels to their zero position, as follows: The shaft 125 as shown in Fig. 3 is provided with a longitudinal keyway 125^a for receiving the free ends of the pawls 132^a pivotally mounted inside of the ratchet wheels 131, as more clearly shown in Figs. 7 and 8. The shaft 125 carries on its end outside of the side plate 127 a setting knob 240, which is rigidly secured to said shaft. The pawls 132^a are so arranged that since the parts of the total indicating mechanism which are mounted on the shaft 125 are free to rotate thereon the total indicating wheels may be advanced without moving the supporting shaft 125. When, however, the supporting shaft 125 is rotated in the same direction as the advance of the total indicating wheels by means of the knob 240, the keyway 125^a engages the free ends of the pawls 132^a and rotates the ratchet wheels 131 and the adding wheels 132 in a forward direction and, since the pawls 132^a are similarly located angularly of the indicating characters on the adding wheels, the zeros on the adding wheels are brought into line with each other and by continued rotation of the adding wheels, may be brought into the reading line or position. 110

While I have shown my invention in the particular embodiment above described, it will be understood that I do not limit myself to this exact construction as I may 115 120 125 130

ploy equivalents known to the art at the time of the filing of this application without departing from the scope of the appended claims.

5. What I claim is:

1. Carry-over mechanism for ordered totalizing indicators comprising the combination of operating mechanism for said totalizing indicators, devices actuated by the 10 operating mechanism for moving the carry-over mechanism to its operative position by each operation of said operating mechanism, and a tripping member actuated by said operating mechanism at the end of each operation thereof for releasing said carry-over mechanism.

2. Carry-over mechanism for ordered totalizing indicators comprising the combination of operating mechanism for said totalizing indicators, devices actuated by the operating mechanism for placing the carry-over mechanism in operative position by each operation of said operating mechanism, a tripping member actuated by said operating mechanism at the end of each operation thereof for releasing said carry-over mechanism, said carry-over mechanism having ordered carrying elements, a pawl for holding each carrying element in operative position, 30 and a releasing device for each pawl actuated by movement of the carrying element of next lower order from its operative position.

3. Carry-over mechanism for ordered totalizing indicators comprising the combination of operating mechanism for said totalizing indicators, devices actuated by the operating mechanism for placing the carry-over mechanism in operative position by each 40 operation of said operating mechanism, a tripping member actuated by said operating mechanism at the end of each operation thereof for releasing said carry-over mechanism, said carry-over mechanism having ordered carrying elements, a pawl for holding each carrying element in operative position, a releasing device for each pawl actuated by movement of the carrying element of next lower order from its operative position, 50 each carrying element having a carrying pawl normally held in inoperative position, and a member carried by each total indicator for releasing the carrying pawl of next higher order when said total indicator is advanced to its zero indication.

4. Carry-over mechanism for ordered total indicator wheels comprising the combination of operating mechanism for said total indicator wheels, said operating mechanism comprising a rock shaft and a set of levers carried by said rock shaft, ordered carry-over slides associated with said total indicating wheels, an arm projecting from each carry-over slide, connecting mechanism between 60 said set of levers and said arms for operat-

ing said carrying-over slides by forward motion of said set of levers, and spring actuated dogs in said connecting mechanism permitting said set of levers to return to normal position without corresponding operation of said carry-over slides. 70

5. Carry-over mechanism for ordered total indicator wheels comprising the combination of operating mechanism for said total indicator wheels, said operating mechanism comprising a rock shaft, ordered carry-over slides associated with the total indicating wheels, connecting mechanism between said slides and said rock shaft for operating said slides by motion in one direction of said shaft, and spring actuated dogs in said connecting mechanism for permitting motion in the other direction of said shaft without operation of said carry-over slides. 80

6. Carry-over mechanism for ordered total indicator wheels comprising the combination of operating mechanism for said total indicator wheels, said operating mechanism comprising a rock shaft, ordered carry-over slides associated with the total 90 indicating wheels, connecting mechanism between said slides and said rock shaft for operating said slides by motion in one direction of said shaft, spring actuated dogs in said connecting mechanism for permitting motion in the other direction of said shaft without operation of said carry-over slides, and detents for holding said carry-over slides in their operated position. 95

7. Carry-over mechanism for ordered total indicator wheels comprising the combination of operating mechanism for said total indicator wheels, said operating mechanism comprising a rock shaft, ordered carry-over slides associated with the total 100 indicating wheels, connecting mechanism between said slides and said rock shaft for operating said slides by motion in one direction of said shaft, spring actuated dogs in said connecting mechanism for permitting motion in the other direction of said shaft without operation of said carry-over slides, detents for holding said carry-over slides in their operated position, and a releasing mechanism for each detent operated 105 by the return to normal position of the carry-over slide of the next lower order. 110

8. Carry-over mechanism for ordered total indicator wheels comprising the combination of operating mechanism for said total indicator wheels, said operating mechanism comprising a rock shaft, ordered carry-over slides associated with the total indicating wheels, connecting mechanism between said slides and said rock shaft for 120 operating said slides by motion in one direction of said shaft, spring actuated dogs in said connecting mechanism for permitting motion in the other direction of said shaft without operation of said carry-over 125 slides. 130

6

8. Slides, detents for holding said carry-over slides in their operated position, a releasing mechanism for each detent operated by the return to normal position of the carry-over slide of the next lower order, devices for releasing the detent of lowest order, and actuating devices between said shaft and said detent releasing devices for releasing said detent of lowest order at the end of each cycle of operation of the shaft.

9. Carry-over mechanism for ordered total indicator wheels comprising the combination of operating mechanism for said total indicator wheels, said operating mechanism comprising a rock shaft, ordered carry-over slides associated with the total indicating wheels, connecting mechanism between said slides and said rock shaft for operating said slides by motion in one direction of said shaft, spring actuated dogs in said connecting mechanism for permitting motion in the other direction of said shaft without operating of said carry-over slides, detents for holding said carry-over slides in their operated position, a releasing mechanism for each detent operated by the return to normal position of the carry-over slide of the next lower order, devices for releasing the detent of lowest order, actuating devices between said shaft and said detent releasing devices for releasing said detent of lowest order at the end of each cycle of operation of the shaft, a carrying pawl carried by each carry-over slide and normally occupying an inoperative position, a spring tending to move each carrying pawl to operative position, a holding pawl for retaining each carrying pawl in inoperative position, a member carried by each total indicating wheel for actuating the holding pawl to release the carrying pawl of next higher order when said total indicating wheel rotates from 9 to zero, and actuating devices connecting the carrying pawls with the carry-over slide operating mechanism for moving the released carrying pawls to inoperative position for each operation of the carry-over slides.

10. Carry-over mechanism for ordered total indicator wheels comprising the combination of operating mechanism for said total indicator wheels, said operating mechanism comprising a rock shaft, ordered carry-over slides associated with the total indicating wheels, connecting mechanism between said slides and said rock shaft for operating said slides by motion in one direction of said shaft, spring actuated dogs in said connecting mechanism for permitting motion in the other direction of said shaft without operating of said carry-over slides, detents for holding said carry-over slides in their operated position, a releasing mechanism for each detent operated by the return to normal position of the carry-over slide of the next lower order, devices for releasing the detent of lowest order, actuating devices between said shaft and said detent releasing devices for releasing said detent of lowest order at the end of each cycle of operation of the shaft, a carrying pawl carried by each carry-over slide and normally occupying an inoperative position, a spring tending to move each carrying pawl to operative position, a holding pawl for retaining each carrying pawl in inoperative position, a member carried by each total indicating wheel for actuating the holding pawl to release the carrying pawl of next higher order when said total indicating wheel rotates from 9 to zero, and actuating devices connecting the carrying pawls with the carry-over slide operating mechanism for moving the released carrying pawls to inoperative position for each operation of the carry-over slides.

10. Carry-over mechanism for ordered total indicator wheels comprising the combination of operating mechanism for said total indicator wheels, said operating mechanism comprising a rock shaft, ordered carry-over slides associated with the total indicating wheels, connecting mechanism between said slides and said rock shaft for operating said slides by motion in one direction of said shaft, spring actuated dogs in said connecting mechanism for permitting motion in the other direction of said shaft without operating of said carry-over slides, detents for holding said carry-over slides in their operated position, a releasing mechanism for each detent operated by the return to normal position of the carry-over slide of the next lower order, devices for releasing the detent of lowest order, actuating devices between said shaft and said detent releasing devices for releasing said detent of lowest order at the end of each cycle of operation of the shaft, a carrying pawl carried by each carry-over slide and normally occupying an inoperative position, a spring tending to move each carrying pawl to operative position, a holding pawl for retaining each carrying pawl in inoperative position, a member carried by each total indicating wheel for actuating the holding pawl to release the carrying pawl of next higher order when said total indicating wheel rotates from 9 to zero, and actuating devices connecting the carrying pawls with the carry-over slide operating mechanism for moving the released carrying pawls to inoperative position for each operation of the carry-over slides.

In witness whereof, I hereunto subscribe my name this 11th day of December, A. D. 1922.

IVAN ENGSTROM.
